(57) **CLAIM**

The ornamental design for a display device portion depicting a graphical user interface as shown and described.

DESCRIPTION

The FIGURE is a front view of a display device portion depicting a graphical user interface, showing the new design.

The broken line showing of the display screen forms no part of the claimed design. The broken line showing of the remainder of the graphical user interface and the unshaded areas there within are for illustrative purposes only and form no part of the claimed design.
